(57) **CLAIM**

The ornamental design for a motorized viewing board, as shown and described.

DESCRIPTION

FIG. 1 is a top plan view of the motorized viewing board used by a person shown in dashed lines.

FIG. 2 is a side plan view of the motorized viewing board shown together with a person using the board in dashed lines.

FIG. 3 is a top perspective view of the motorized viewing board.

FIG. 4 is a bottom perspective view of the motorized viewing board; and,

FIG. 5 is a rear perspective view of the motorized viewing board.

The broken lines depicting a person are for illustrative purposes only and form no part of the claimed design.
